UNITED STATES PATENT OFFICE.

SETH WM. BABBITT, OF MERIDEN, CONNECTICUT.

DESIGN FOR A DISH.

SPECIFICATION forming part of Design No. 22,799, dated September 26, 1893.

Application filed September 4, 1893. Serial No. 484,790. Term of patent 3½ years.

To all whom it may concern:

Be it known that I, SETH W. BABBITT, of Meriden, in the county of New Haven and State of Connecticut, have invented a new Design for a Dish; and I do hereby declare the following, when taken in connection with accompanying drawings and the letters of reference marked thereon, to be a full, clear, and exact description of the same, and which said drawings constitute part of this specification, and represent, in—

Figure 1, a top view of a dish containing my design; Fig. 2, a sectional view thereof.

This invention relates to a design for a dish, and consists in the configuration and ornamentation as shown in the accompanying illustrations.

The general shape of the body A, of the dish, is rectangular, its corners being rounded, and its side-walls B B and end-walls C C being composed of combinations of graceful curves, extending inward to the bottom D of

the dish, from which the said sides are clearly defined. The said body of the dish is surrounded by a horizontal flange E, ornamented by a series of foliated scrolls F, G, and H, differentiated in curvature and foliation from each other, and placed substantially end to end, the scrolls at the ends and corners of the dish and at the middle of the sides thereof, being enriched with leaf-like forms I, J and K, differentiated from each other, but all in the rococo style of ornamentation, which characterizes the entire dish.

I claim—

The design for a dish as herein shown and described.

In testimony whereof I have signed this specification in the presence of two subscribing witnesses.

SETH WM. BABBITT.

Witnesses:

HERBERT H. GEDNEY,
G. S. MARTINDALE.
